WINDOW SHADE MOUNTING

Elmer F. Pidgeon, Spiceland, Ind.

Application January 8, 1942, Serial No. 426,073

1 Claim. (Cl. 160—267)

This invention relates to an improved window shade mounting and more particularly to a mounting which will cooperate with an opaque window shade to effectively prevent the passage of light rays through the window or other opening equipped with the invention.

More particularly, it is an aim of the invention to provide a box adapted to be attached to the upper part of a window frame and adapted to contain a shade roller and shade and having means for readily opening the box for applying or removing the shade and roller.

Another object of the invention is to provide channel members having ends extending into the box and which are adapted to slidably receive the side edges of the window shade when the shade is in an extended or drawn position.

Another object of the invention is to provide a window shade of novel construction which can be drawn sufficiently so that it will rest on the bottom rail of the window frame and which, when so drawn, can be readily pulled by a pull cord to permit the roller to rewind the shade thereon.

Other objects and advantages of the invention will hereinafter become more fully apparent from the following description of the drawing, which illustrate a preferred embodiment thereof, and wherein:

Figure 1 is a fragmentary horizontal sectional view of a window frame and shade mounting on a plane indicated by the line 1—1 of Figure 2, showing the improved invention.

Figure 2 is an enlarged fragmentary transverse vertical view taken substantially along the plane of the line 2—2 of Figure 1.

Figure 3 is a perspective view of one end of one section of one of the channel members, and

Figure 4 is a similar view of the other section.

Referring more particularly to the drawing, wherein like reference characters designate like or corresponding parts throughout the different views, 10 designates generally a conventional window frame including a top rail 11, side rails 12, and a bottom rail or sill 13. The frame 10 forms no part of the invention but is shown and described merely to better illustrate the application of the window shade mounting, designated generally 14 and comprising the invention.

The shade mounting 14 includes a box, designated generally 15 which is adapted to be disposed against the inner face of the top rail 11 and which is preferably attached to a top piece 16 of the frame 10 by means of fastenings 17.

which extend through openings 18 in the top 19 of the box 15. If desired, the box 15 can be attached to the upper rail 11 by extending the fastenings 17 through the rear wall 20 of the box. 5 The box 15 includes end walls 21 to the inner sides of which are attached shade roller brackets 22 for supporting a conventional spring winding shade roller 23 within the box 15 and longitudinally thereof. The box 15 is provided with a front wall 24 having inturned flanges 25 at the ends thereof for engaging the inner sides of the end walls 21. The front wall 24 is pivotally connected to the end walls 21 by means of suitable pivot means 26 which extend through the end walls and the flanges 25, adjacent their upper ends. The box 15 also includes a bottom 27 which forms an angular continuation of the lower edge of the front wall 24 and which is disposed substantially at a right angle thereto. The front wall 24 and bottom 27 can be swung outwardly and upwardly on the pivot 26 to the position, as seen in dotted lines of Figure 2, for exposing the interior of the box 15. The free edge of the bottom 27 is bent inwardly and back upon itself to provide a rounded free edge 28 which is spaced from the rear wall 20 when the bottom 27 is in a horizontal, closed position as seen in Figure 2. The edge 28 and the rear wall 20 combine to form a downwardly opening slot 29 which extends the length of the box 15.

A channel member, designated generally 30, is mounted on the face of each of the side rails 12 and said channel members have upper ends which extend into the box 15 through the ends of the slot 29, as seen in Figure 2, and opposite, lower ends, which rest on the upper side of the sill 13. The channel members 30 each include a section 31, as seen in Figure 5, and a section 32, as seen in Figure 6. The sections 31 each comprise an elongated strip having an angularly disposed longitudinal edge forming a flange 33. The sections 32 each include an elongated strip which is folded lengthwise and the edges of which are angularly disposed to form flange portions 34 which are spaced apart to provide a slot 35 therebetween. The strips 31 are adapted to be fastened against the faces of the side rails 12 by means of fastenings 36 and with the flanges 33 projecting outwardly from the outer edges of the strips 31. The strips 32 are then applied to the strips 31 by positioning the flanges 33 in the slots or channels 35 and the flanges 33 and the flange portions 34 are detachably connected by fastenings 37.

A window shade 38 is wound on the roller 23

and has its free end extending downwardly through the slot 29 and its longitudinal edges disposed in the channels 30. The shade 38 is preferably formed of a black material which is opaque to prevent the passage of light therethrough. A bar 39 is disposed in a hem 40 at the lower, free end of the shade 38 and a second bar 41 is disposed in a hem portion 42 of the shade 38 near its bottom but spaced therefrom so that there will be a shade portion 43 between the bars 39 and 41, each of which is disposed transversely of the shade 38. A pull cord 44 is attached to the upper bar 41.

From the foregoing, it will be obvious that the shade 38 can be drawn by the cord 44 until the lower bar 39 is resting on the sill 13 to prevent the passage of light between the sill and shade. The inwardly opening channels 30 will contain the longitudinal edges of the shade 38 and combine therewith for preventing the passage of light between the side rails 12 and the shade 38. The box 15 will combine with the shade 38 to prevent the passage of light at the top of the window opening. When it is desired to raise the shade 38 the shade portion 43 will permit the bar 41 to be pulled downwardly sufficiently to release the latch of the shade roller to cause the roller to rewind the shade thereon. Obviously, if the pull cord 44 were attached to the bottom bar 39 the shade could not be raised after being drawn to a fully lowered position.

If desired, the box 15 can be mounted in the top of the window opening and attached to the inner side of the top rail 11 and the channels 30 can be attached to the inner sides of the side rails 12 and disposed in the window openings and when thus disposed, the fastenings 37 could be utilized for not only connecting the channel sections 31 and 32 but for also mounting the channels 30 in the window opening by extending into the side rails 12.

In Figure 9 a slightly modified form of the invention is shown wherein an additional channel member 30 is utilized. The additional channel member 30 is mounted on the sill 13 and is fastened thereto, so as to open upwardly, by screws 37 which extend downwardly through the flanges 33 and 34, for connecting the channel sections 31 and 32, and into the sill 13 for mounting the channel member 30 thereon. The lower ends of the channel members which are attached to the side rails 12 extend into the ends of the last mentioned channel member. The face of the side rails 12 can be recessed to receive the inner section 31 of the bottom channel member, when the side channel members 30 are attached to the rails 12, as in Figures 1 to 7. It will thus be seen that the bottom edge of the shade 38, including the bar 39, will be received in the bottom channel member 30 to provide a shield entirely surrounding the shade, which is advantageous where all light rays must be excluded. The bottom channel member could be mounted in the same manner as the side channel members, where the shield is disposed on the face of a wall around a window opening.

Various modifications and changes are contemplated and may obviously be resorted to, provided they fall within the spirit and scope of the invention as hereinafter defined by the appended claim, as only a preferred embodiment thereof has been disclosed.

I claim as my invention:

A channel member including an elongated strip having a flange projecting angularly from one longitudinal edge, a second strip having an angular slotted flange projecting from one longitudinal edge thereof for receiving the first mentioned flange, and fastenings for detachably connecting the flanges.

ELMER F. PIDGEON.
